STOVE

Clement Ehret, White Plains, N. Y.

Application January 7, 1939, Serial No. 249,673

14 Claims. (Cl. 126—200)

This application is a continuation in part of my copending Patent No. 2,143,411, issued on January 10, 1939, which was a division of my copending Patent No. 2,102,616, issued December 31, 1937, which disclose a stove having a rotatable stove body mounted on a relatively fixed base and which stove body is provided with one or more ovens.

The present invention provides novel and efficient means to permit of the illumination of such ovens, so that roasts, etc., may be readily observed, and inspected without removing them from the ovens or opening the oven doors.

The invention further provides means whereby a transparent panel in an oven door may be wiped clean of vapor or other deposits, so that the interior of the oven may be readily seen therethrough and provision is made whereby this wiping operation will simultaneously act upon the illuminating means to remove like deposits therefrom, the illuminating means and the wiping means being preferably interlocked, so that the illumination of the oven may be controlled through the operation of the wiping means.

Features of the invention, other than those adverted to, will be apparent from the hereinafter detailed description and claims, when read in conjunction with the accompanying drawings.

The accompanying drawings illustrate different practical embodiments of the invention, but the constructions therein shown are to be understood as illustrative, only, and not as defining the limits of the invention.

Figure 1 shows a stove embodying the present invention, partly in central vertical section in the plane of the line 1—1 of Figure 2, and partly in elevation.

Figure 2 is an elevation of such stove, as viewed from the right hand side of Figure 1.

Figure 3 is a front to rear section through an oven showing a modified form of the invention wherein the illuminating means and a transparent panel in the oven door may be wiped clean of extraneous deposits. This section is taken substantially in the plane of the line 3—3 of Figure 4.

Figure 4 is a front elevation of the structure of Figure 3 with the oven door closed.

Figure 5 is a fragmental section taken substantially in the plane of the line 5—5 of Figure 3 with associated wiring diagram.

Figure 6 is a section perspective showing a further form of the invention.

Figures 7 and 8 are sections on the lines 7—7 and 8—8.

Referring first to Figures 1 and 2 of the drawings, 1 designates a suitable hollow standard, 5 shown as comprising a relatively broad base 2 having an upstanding cylindrical portion 3. The upper end of the cylinder 3 is open, and projecting thereinto is a hollow plunger 4, mounted within the cylinder 3 for rotation and vertical adjustment. This vertical adjustment may be accomplished in different ways and by means of various types of mechanism, but, the plunger 4 is shown as threaded at 5 and cooperating with these threads is an adjusting hand wheel 6 having a threaded hub 7 screwed on to the plunger 4. In the under side of the hub 7 is formed a ball race and in the upper end of the cylinder wall is formed a complementary ball race and anti-friction bearings 8 are housed within these complementary ball races, so as to permit rotation of the hand wheel 6 for the purpose of raising and lowering the plunger with respect to one standard when said plunger is held against rotation. The plunger and hand wheel may also 15 rotate together while the base remains stationary. The upper end of the plunger is flanged at 9 and this flange is secured in any suitable way to the under side of the stove body, indicated generally by the reference character 20 10. The stove body may have one or more ovens and each oven may have one or more doors.

The details of construction of the stove body may, of course, be varied within wide limits depending upon the type of fuel used and also upon 35 the views of different stove designers and the present invention is to be understood as not limited to these details other than as hereinafter specifically pointed out as important to this invention.

Gas is fed to the stove body through a pipe 32 rigid with the stove body and extending downwardly within and coaxially with the plunger 4 and connected to a fuel supply pipe 33 by any suitable connection which will preclude the leakage of gas but which will permit of rotation of the stove body and raising and lowering of the latter. An ordinary hose connection of flexible character will serve this purpose, but, for the purpose of illustration, the pipe 33 is shown as 45 extending into the pipe 32 with an associated packing gland or stuffing box 34 to preclude leakage. This arrangement allows of rotation and change of elevation in the stove body without interfering with the supply of fuel. The same general arrangement may be used to supply oil, if 50 55

the stove is an oil burner, and it will of course be understood that, in an electric stove, suitable wiring connections and heating elements will take the place of gas connections and burners.

One form of oven illuminating means which I have chosen as illustrative of the present invention is shown in detail in Figures 1 and 2 of the drawings. Here, such means embodies hinged housings 55 positioned over openings in the sides of the oven and each of which openings is closed at its inner side by a transparent or translucent window 56 of appropriate material to stand the heat of the oven, such as Pyrex glass. In each housing is mounted a lamp socket 57 adapted to receive an incandescent lamp 58, electric current to which is supplied through wires housed within conduits 59. These conduits lead to the interior of the hollow plunger 4 and additional conduits 60 lead to push buttons 61 or other manually controlled means positioned adjacent each oven door or in any other desired position. The wiring connections are indicated diagrammatically in Figure 1. Here, the wires 62 and 63 which feed this system are connected to brushes 64 and 65, respectively, mounted upon a ring of insulation 66 fixed on the interior of the plunger 4. An insulating disk 67 is supported on the lower end of the pipe 32 and held loosely between collars 68 and 69 screwed on to said pipe, so that the pipe 32 is free to rotate within the insulating disk which is raised and lowered with the stove body. The outer periphery of this disk 67 has one or more projections which extend into vertical keyways 74 in the cylinder wall, so that, while the disk is free to raise and lower with the stove body, it is held against rotation by the keyways 74.

On this insulating disk 67 is mounted two commutator rings 70 and 71 engaged by the brushes 64 and 65, respectively, at all times and these commutator rings are fed by wires 72 which form parts of a feed cable 73, looped within the hollow base to allow of raising and lowering movement of the stove body while permitting uninterrupted feed of current to the wires 62 and 63.

When a person desires to inspect the contents of the oven, one of the push buttons 61 may be pressed to energize the lamps 58 and illuminate the entire interior of the oven. The sources of illumination may be placed otherwise than specified, but the showing of the drawings is not only convenient, but thoroughly efficient. The advantage of placing the lamps 58 in housings, hinged to the stove body, is that these housings may be open at any time for replacement of lamps, and while the lamps are thus positioned to properly illuminate the interior of the oven, they are removed from the direct heat or vapor from the latter. The housings for the illuminating means may be mounted either inside or outside the oven and should be ventilated to the atmosphere by perforations or holes to preclude fogging of the lamps.

Each of the oven doors is provided with a transparent panel 50, e. g., pyrex glass or the like which is able to withstand the heat of the oven. By this means it is possible to observe the interior of the oven and the contents thereof, while the same is illuminated by the lamp or lamps 58 and without necessitating the opening of the door. Panel 50 may, if desired, be in the form of a magnifying glass or lens.

It will of course be understood that, while I have shown the stove body in considerable detail in the drawings, I do not wish to limit the pres-

ent invention in this connection for any appropriate stove body may be employed in connection with this invention.

In Figures 3, 4 and 5 I have illustrated a modified form of the invention. Here the oven 101 has a drop door 102 hinged at 103 at its bottom and this door has a transparent panel 104 through which the interior of the oven may be observed. The panel 104 is set into the door so as to be flush with the inner face thereof and supported by the oven, immediately above the door, is a light casing 105 which has a light penetrable panel 106 facing rearwardly into the confines of the oven and lying in substantially the same plane as the panel 104. In this housing 105 is enclosed a lamp 107, shown as of elongated form and mounted in any appropriate socket, so that it can be readily changed. When the lamp is lit it will illuminate the interior of the oven through the panel 106 and such illuminated interior may be viewed from the exterior of the oven through the panel 104.

The lamp and wiper are shown as mounted at the upper portion of the oven but they may be mounted at the side or bottom thereof or in any other convenient position. Furthermore, the lamp mounting may be made accessible from the outside of the oven.

When an oven is in use the panels 104 and 106 both tend to accumulate steam and other extraneous matter which interferes with their proper functions and it is desirable therefore to clean or wipe these panels free from such deposits when they are to be used to view the contents of the oven. The present invention provides a wiper which may be operated to wipe both panels. This wiper, indicated at 108, may conveniently comprise asbestos wool or any other suitable material of a non-combustible nature and it is mounted upon an arm 109 which extends through a slot 110 in the inner side wall of the oven and is rigidly secured to a spindle 111 mounted for oscillation on the oven body. This spindle extends through the front wall of the oven and carries a handle 112 by means of which it may be oscillated, so as to cause the wiper to traverse both the panels 104 and 106. The arm 109 is preferably of a resilient character so as to hold the wiper 108 firmly against the panels when the oven door is closed. Thus a person desiring to view the interior of the oven may operate the handle 112 and thereby move the wiper over the panel 104 of the door, so as to obtain a clear vision into the interior of the oven. At the same time continued travel of the wiper above the door opening will cause it to traverse the panel 106 back of the lamp and thus keep this panel clean, so that the oven may be efficiently illuminated from such lamp. The oven door is shown as fitting flush with the lamp housing 105, so as to provide for substantially uninterrupted travel of the wiper from one panel to the other.

The control of the lamp may be accomplished in various ways as by a manually operable switch, but I preferably make this control automatic and interlock the same with the wiper. Thus, as shown best in Figure 5, the lamp 107 is included in a circuit 113 fed from any suitable external source of current supply 114 and in this circuit is also included two brush contacts 115 and 116. These brush contacts are supported on a housing 117 which embraces the spindle 111 of the wiper and is supported rigidly in position with respect to the oven body. The contact brushes are, moreover, insulated with respect to this casing 117.

and with respect to the casing 117 and to each other and they are adapted to ride upon a ring of insulation 118 fixed on the spindle 111. Set into this ring of insulation is a conductor bridge 119 of such size that, when the wiper is in a predetermined position, the conductor 119 will bridge the brush contacts and complete the circuit to the lamp 107.

The parts may be so arranged that the lamp can be lit in any predetermined position of the wiper, but I prefer to have the wiper operate throughout the major portion of its swing without affecting the lamp and to only close the circuit when the wiper is in its lowermost position substantially as indicated in Figure 4.

With this arrangement the user of the stove may operate the wiper to clean the panels and then, by moving the wiper to its lowermost position, energize the lamp and illuminate the oven, so as to render the interior thereof visible through the door panel. When the wiper is not in use, it is swung in a clockwise direction into the idle position of Figure 3, where it is out of contact with the door and free and clear of the door opening and wherein the circuit to the lamp is broken. In other words, the wiper is movable into a position wherein it is removed from the door and the door opening of the oven, so as to leave said door opening unobstructed by the wiper, whereby large roasts may be moved into and out of the oven without fear of contact with the wiper. Furthermore the wiper in this position is entirely out of the way for it is mounted on and supported by the stove body independently of the oven door and consequently the door is wholly unencumbered when it is opened. So far as I am aware no structure of this kind has ever before been proposed. Such wipers as have been suggested have been mounted on the oven door and not independently of the door and consequently they constitute an encumbrance on the door which is particularly undesirable and annoying when the door is open.

I wish it understood that the structure which I have shown in Figures 3, 4, and 5, and similar structures of which this disclosure is merely illustrative, may be employed in stoves of all kinds, employing any kind of fuel and irrespective of vertical or rotary adjustment of a stove body. In fact, this embodiment of the invention may be used on any of the types of stoves now in use in general application and will be found to give highly satisfactory results in this regard. It may also be used to advantage in a stove of the character shown in Figures 1 and 2, wherein the stove body is rotatable and vertically adjustable with respect to the base. In which latter case, current may be fed to the lamp 107 through connections like those disclosed in Figures 1 and 2, so as to permit of such adjustments without interfering with the feed of current to the lamp. Likewise the oven doors of Figures 1 and 2 may be equipped with wipers of the character shown in Figures 3, 4 and 5, and they may control the circuits to the lamps which illuminate the interior of the oven. In Figures 1 and 2, the illustrative fuel for the stove heating elements is gas and thus independent electric wiring must be used for the lamps to illuminate the ovens and this applies in all cases where other than electricity is used as the heating medium.

It will be understood, however, that with electric stoves and where the electricity is the heating medium, the circuits of the oven illuminating lamps may be coupled in multiple into the heat-

ing element circuits with the control switches in the lamp circuit.

Figures 6-8 show another form of the invention. Here the stove body 120 is so formed as to provide, adjacent the front of the oven, a recess or seat 121 having the cross section of a quarter of a circle and in this recess is seated a substantially cylindrical lamp housing 122. This housing is supported for axial rotation by means of a trunnion 123 at one end and a relatively rigid tubular shaft 124 at the other end. A lamp socket 125 is fixed on the inner end of this shaft and detachably supports a lamp 126. Wires for feeding electric current to the lamp lead through the hollow shaft 124 to contacts 127 and 128, fixed on an insulating rotor rigid with the shaft. The rotor is enclosed within a cap 129 carrying a strip of insulation 130 and this strip carries brushes 131 and 132 to contact with the contacts 127 and 128. A handle 133 is attached to the outer end of the shaft to rotate the latter so that in one position the contacts will feed current to the lamp 126 and in other positions the lamp will be de-energized.

The parts are so related that, when the lamp is illuminated, an opening 134 in the wall of the lamp housing will be exposed to the interior of the oven and the latter will be illuminated by the lamp. When the housing is rotated to shut off the current to the lamp the opening 134 will move into juxtaposition with the seat 121 and seal the oven against loss of heat at this point. Vent openings 135 in the lamp housing 122, at this time, vent the interior of said housing to the atmosphere to keep the lamp from fogging. The oven door is indicated at 136 and its transparent panel at 137. A wiper is associated with the panel but is not shown in these figures.

The rotary construction of Figures 6-8 may be placed in a convenient position with respect to the oven and its incorporation into the stove construction may be accomplished in other ways without departing from this invention.

Having thus fully described the invention, what I claim as new and desire to secure by Letters Patent is:

1. A stove comprising a stove body including an oven having a door, a transparent panel in said door, a lamp for illuminating the interior of the oven, a lamp housing enclosing the lamp and having a light penetrable panel, and a wiper operable to wipe the panels of both the door and lamp housing.

2. A stove comprising a stove body including an oven having a door, a transparent panel in said door, a lamp for illuminating the interior of the oven, a lamp housing enclosing the lamp and having a light penetrable panel, a wiper mechanism including a wiper operable to wipe the panels of both the door and lamp housing, and a lamp controlling switch operatively connected to the wiper mechanism and controlled thereby.

3. A stove comprising a stove body including an oven and having a transparent observation panel in at least one of the walls thereof, a light housing for illuminating the interior of the oven and having a light penetrable panel in one of its walls, and a wiper mounted to traverse the faces of both of said panels.

4. A stove comprising a stove body including an oven and having a transparent observation panel in one of the walls thereof, a light housing for illuminating the interior of the oven and having a light penetrable panel in one of its walls, a wiper mechanism including a wiper

mounted to traverse the faces of both of said panels, a lamp in the lamp housing, and a lamp energizing circuit including a switch operatively connected to the wiper mechanism and controlled thereby.

5. A stove comprising a stove body including an oven and having a transparent observation panel in one of the walls thereof, a light housing for illuminating the interior of the oven and having a light penetrable panel in one of its walls, and a wiper mounted to traverse the faces of both of said panels, a lamp in the lamp housing, and a circuit including the lamp and a switch, said switch being operably interlocked with the wiper to close the circuit to the lamp when the wiper is in a predetermined position.

6. A stove comprising an oven having a transparent observation panel in one of its walls, a wiper for wiping the inner face of said panel, a lamp for illuminating the interior of the oven, a lamp circuit including a switch, and a manually operable member operatively connected to both the wiper and the switch to control the operations of both of them.

7. A stove comprising a stove body including an oven having a door, a transparent panel in said door, a lamp for illuminating the interior of the oven, a circuit including said lamp, a wiper operable to wipe the inner face of said panel, a switch included in said circuit for controlling the operations of said lamp, and a common operating member connecting with both the wiper and the switch for operating both of them.

8. A stove comprising a stove body including an oven having a door, a transparent panel in said door, a lamp for illuminating the interior of the oven, a circuit including said lamp, a wiper operable to wipe the inner face of said panel, a switch included in said circuit for controlling the operations of said lamp, and a common operating member connecting with both the wiper and the switch for operating both of them, said switch being set to close the circuit to the lamp only when the wiper is in predetermined positions, with the lamp deenergized when the wiper is in other positions.

9. A stove comprising a stove body including an oven, a light housing for illuminating the interior of the oven and having a light penetrable panel in one of its walls through which light may pass into the interior of the oven, a wiper mounted to traverse the face of said panel which is exposed to the oven interior, a lamp in the lamp housing, a circuit including the lamp and a switch, and a common operating member connecting with both the wiper and the switch for operating both of them.

10. A stove comprising a stove body including an oven, an oven door mounted on the stove body to open and close the oven, a transparent panel in said door, a wiper operable on the inner face of the transparent door panel when the door is closed and supported on the stove body independently of said oven door, whereby said oven door is wholly unencumbered by the wiper.

11. A stove comprising a stove body including an oven provided with a door opening, an oven door mounted on the stove body to open and close the door opening of the oven, a transparent panel in said door, and a wiper operable on the inner face of the transparent door panel when the door is closed and supported on the stove body independently of said oven door, whereby said oven door is wholly unencumbered by the wiper, said wiper being movable into a position removed from said door and door opening to leave the door opening of the oven unobstructed by the wiper.

12. A stove comprising a stove body including an oven, an oven door mounted on the stove body to open and close the oven, a transparent panel in said door, a shaft supported by the stove body independently of said door and extending from the exterior to the interior of the stove body externally of the confines of the door, a wiper supported on the shaft interiorly of the stove body and operable by said shaft to wipe the inner faces of said panel when the door is closed, and an operating handle on said shaft exteriorly of the stove body.

13. A stove comprising a stove body including an oven, an oven door mounted on the stove body to open and close the oven, a transparent panel in said door, a shaft supported by the stove body independently of said door and extending from the exterior to the interior of the stove body externally of the confines of the door, a wiper supported on the shaft interiorly of the stove body and operable by said shaft to wipe the inner face of said panel when the door is closed, an operating handle on said shaft exteriorly of the stove body, a lamp positioned to illuminate the interior of the oven, a circuit including said lamp, and a switch in said circuit connected to said shaft to be operated therewith, whereby said handle controls the operations of both the wiper and the lamp.

14. A stove comprising a stove body including an oven, an oven door mounted on the stove body to open and close the oven, a transparent panel in said door, a shaft supported by the stove body independently of said door and extending from the exterior to the interior of the stove body externally of the confines of the door, a wiper supported on the shaft interiorly of the stove body and operable by said shaft to wipe the inner face of said panel when the door is closed, an operating handle on said shaft exteriorly of the stove body, a lamp positioned to illuminate the interior of the oven, a circuit including said lamp, and a switch in said circuit connected to said shaft to be operated therewith, whereby said handle controls the operations of both the wiper and the lamp, said switch being set to close the circuit to the lamp when the wiper is in predetermined positions while in other positions of the wiper the lamp is deenergized.

CLEMENT EHRET.
